(57) **ABSTRACT**

A heat exchanger, that connects to a first pipe through which a refrigerant flows, includes: heat transfer tubes extending in a first direction; and a header connected to the heat transfer tubes. The header includes: a first member including a first portion connected to the heat transfer tubes; and a second member disposed between the first pipe and the first portion. The second member includes: a first wall and a second wall that each extend in the first direction; and a coupling portion that couples the first wall to the second wall. The first pipe communicates with each heat transfer tube through a space delimited by the first wall and the second wall.

HEAT EXCHANGER AND HEAT PUMP APPARATUS

TECHNICAL FIELD

The present disclosure relates to a heat exchanger and a heat pump apparatus.

BACKGROUND

A known refrigerant cycle apparatus such as an air conditioning apparatus includes a heat exchanger including a heat transfer tube through which a refrigerant flows and a header to which the heat transfer tube is connected.

For example, Patent Literature 1 (WO 2015/004719 A1) discloses a heat exchanger including a gas header that includes a plurality of plate-shaped members stacked on top of each other, the plate-shaped members each having an opening.

PATENT LITERATURE

Patent Literature 1: WO 2015/004719 A1

It is necessary to increase the number of plate-shaped members in order to secure a wide space in the header that includes the plurality of plate-shaped members stacked on top of each other, the plate-shaped members each having the opening.

SUMMARY

In one or more embodiments, a heat exchanger including a header enables a reduction in parts count even when a large space is secured in the header, and also provides a heat pump apparatus.

In one or more embodiments, a heat exchanger is connected to a first pipe through which a refrigerant flows. The heat exchanger includes a plurality of heat transfer tubes, and a header connected to the heat transfer tubes. The header includes a first member and a second member. The first member includes a first portion connected to the heat transfer tubes. The second member is disposed between the first pipe and the first portion. The second member includes a first wall, a second wall, and a coupling portion. The first wall and the second wall each extend in a first direction in which the heat transfer tubes extend. The coupling portion couples the first wall to the second wall. The first pipe communicates with each heat transfer tube through a space defined by the first wall and the second wall.

In the heat exchanger, the first and second walls of the second member extend in the first direction in which the heat transfer tubes extend. With this configuration, the second member secures the space defined by the first wall and the second wall.

In one or more embodiments of the heat exchanger, the coupling portion couples an end of the first wall in the first direction to an end of the second wall in the first direction.

It is sufficient for the coupling portion to couple the end of the first wall in the first direction to the end of the second wall in the first direction. For example, the coupling portion may couple the first wall to the second wall on the opposite side to the heat transfer tubes in the first direction.

In the heat exchanger, the coupling portion couples the end of the first wall to the end of the second wall. This configuration therefore secures the space defined by the first wall and the second wall wide with ease.

2

In one or more embodiments of the heat exchanger, the coupling portion couples a portion of the first wall, the portion being different from two ends of the first wall in the first direction, to a portion of the second wall, the portion being different from two ends of the second wall in the first direction.

The heat exchanger enables strength enhancement to the second member since the coupling portion couples a portion of the first wall in the first direction, the portion being different from two ends of the first wall in the first direction, to a portion of the second wall in the first direction, the portion being different from two ends of the second wall in the first direction.

In one or more embodiments of the heat exchanger, the first portion has a plate (planar) shape.

Preferably, the first member has a plate shape expanding perpendicularly to a direction in which the heat transfer tubes extend.

The heat exchanger suppresses occurrence of a situation in which an unnecessary space is defined around a portion of each heat transfer tube in the header, since the heat transfer tubes are connected to the plate-shaped first portion.

In one or more embodiments of the heat exchanger, the second member includes a first protrusion and a second protrusion. The first protrusion protrudes from the first wall toward the second wall. The first protrusion is located closer to the heat transfer tubes than the coupling portion is. The second protrusion protrudes from the second wall toward the first wall. The second protrusion is located closer to the heat transfer tubes than the coupling portion is. A minimum distance between the first protrusion and the second protrusion is shorter than a maximum width of each heat transfer tube in section.

According to one or more embodiments, the first and second protrusions of the second member define a degree of insertion of the heat transfer tubes into the header.

In one or more embodiments of the heat exchanger, the coupling portion couples a portion of the first wall, the portion being located closer to the first pipe with respect to a center of the first wall in the first direction, to a portion of the second wall, the portion being located closer to the first pipe with respect to a center of the second wall in the first direction. The first protrusion is located closer to the heat transfer tubes with respect to the center of the first wall in the first direction. The second protrusion is located closer to the heat transfer tubes with respect to the center of the second wall in the first direction.

The heat exchanger ensures a wide space defined by the ends of the heat transfer tubes, the coupling portion, the first wall, and the second wall.

A heat exchanger according to one or more embodiments further includes a third member. The third member is disposed so as to face a side, where the second member is disposed, of the first portion of the first member. The first portion has a plurality of first openings into which the heat transfer tubes are inserted. The third member has a plurality of second openings into which the heat transfer tubes are inserted. Each first opening has a portion overlapping the respective second opening as seen in the first direction.

According to one or more embodiments, the heat transfer tubes are fixed with the heat transfer tubes inserted into the first openings in the first portion. Since the first portion overlaps the third member, a thickness of an overlapping portion of the first portion and the third member is secured, which enhances strength. This configuration thus secures the strength of the overlapping portion of the first portion and the third member even in a case where the first portion is

formed thin for reducing friction between an outer peripheral face of each heat transfer tube and the corresponding first opening, the friction being caused in inserting the heat transfer tubes into the first openings.

In one or more embodiments of the heat exchanger, each second opening of the third member is larger than the corresponding first opening of the first portion as seen in the first direction. An edge of each second opening of the third member is located outward of an edge of corresponding first opening of the first portion as seen in the first direction.

According to one or more embodiments, in joining the first portion to the third member by brazing, an excessive brazing material is moved to a region in each second opening, the region being located outside the heat transfer tubes. This configuration therefore suppresses occurrence of a situation in which the flow paths in the heat transfer tubes are filled with the brazing material.

A heat exchanger according to one or more embodiments further includes a fourth member to which the first pipe is connected. The first member includes wall surface portions and claws. The wall surface portions respectively extend from two ends of the first portion toward the first pipe respectively along the first wall and the second wall. The claws are disposed on ends of the wall surface portions opposite to the first portion. The claws extend to come close to each other. The claws are in contact with a surface of the fourth member opposite to the first portion.

It should be noted that the two ends of the first portion may be two ends of the first portion as seen in a longitudinal direction of the first portion.

According to one or more embodiments, the fourth member is held by the claws of the first member. The second member is thus surrounded by the first member and the fourth member.

In a case where each of the first member and the fourth member is made of pitting metal, the corrosion resistance around the header is improved.

In one or more embodiments of the heat exchanger, each heat transfer tube is a flat tube. Each flat tube has a flat face.

Preferably, the flat tubes each have such a sectional shape that a width of the first portion in the longitudinal direction is shorter than a width of the first portion in a direction perpendicular to the longitudinal direction.

In one or more embodiments of the heat exchanger, the first pipe is a gas pipe.

It should be noted that the refrigerant flowing through the gas pipe is not limited to a refrigerant in a gas state, but may be a refrigerant in a gas-liquid two-phase state. Such a refrigerant in a gas-liquid two-phase state preferably has a degree of dryness that is not less than 0.8, for example.

The heat exchanger enables pressure resistance strength enhancement to the header connected to a gas pipe, with ease.

In one or more embodiments, a heat pump apparatus includes the heat exchanger according to any of the above-described embodiments.

BRIEF DESCRIPTION OF THE DRAWINGS

FIG. 1 is a schematic configuration diagram of an air conditioning apparatus.

FIG. 2 is a schematic perspective view of an outdoor heat exchanger.

FIG. 3 is a partially enlarged view of a heat exchange part of the outdoor heat exchanger.

FIG. 4 is a schematic diagram of the heat exchange part in which a heat transfer fin is mounted to a flat tube.

FIG. 5 is a diagram of a flow of a refrigerant in the outdoor heat exchanger functioning as an evaporator for the refrigerant.

FIG. 6 is an external view of a gas header to which a main gas-refrigerant pipe connection portion is connected as seen in side view.

FIG. 7 is a sectional view of the gas header as seen in plan view.

FIG. 8 is a sectional view of the gas header to which the main gas-refrigerant pipe connection portion and the flat tube are connected as seen in plan view.

FIG. 9 is a schematic diagram of a rear side of a first member.

FIG. 10 is a schematic diagram of a rear side of a third member.

FIG. 11 is a schematic diagram of a rear side of a second member.

FIG. 12 is an external perspective view of the second member.

FIG. 13 is a schematic diagram of a rear side of a fourth member.

FIG. 14 is a projection view of a positional relationship among openings in a case where the first member is seen from its rear side.

FIG. 15 is a sectional view of a gas header to which a main gas-refrigerant pipe connection portion and a flat tube are connected as seen in plan view in Modification A.

FIG. 16 is a projection view of a positional relationship among openings in a case where a second member is seen from its rear side in Modification A.

FIG. 17 is a sectional view of a gas header as seen in plan view in Modification B.

DETAILED DESCRIPTION

A description will be given of an air conditioning apparatus including a heat exchanger in accordance with one or more embodiments.

(1) Configuration of Air Conditioning Apparatus

A description will be given of an air conditioning apparatus 1 with reference to the drawings.

FIG. 1 is a schematic configuration diagram of the air conditioning apparatus 1 including an outdoor heat exchanger 11 corresponding to a heat exchanger according to one or more embodiments of the present disclosure.

The air conditioning apparatus 1 (which is an example of a heat pump apparatus) is configured to perform a vapor compression refrigeration cycle, thereby cooling and heating an air conditioning target space. Examples of the air conditioning target space may include, but not limited to, spaces in buildings such as an office building, a commercial facility, and a residence. It should be noted that the air conditioning apparatus is merely an example of a refrigerant cycle apparatus. The heat exchanger according to one or more embodiments of the present disclosure may be used for other refrigerant cycle apparatuses such as a refrigerator, a freezer, a water heater, and an underfloor heating apparatus.

As illustrated in FIG. 1, the air conditioning apparatus 1 mainly includes an outdoor unit 2, an indoor unit 9, a liquid-refrigerant connection pipe 4, a gas-refrigerant connection pipe 5, and a control unit 3 configured to control components of the outdoor unit 2 and components of the indoor unit 9. The liquid-refrigerant connection pipe 4 and the gas-refrigerant connection pipe 5 connect the outdoor unit 2 to the indoor unit 9. In the air conditioning apparatus

1, the outdoor unit 2 and the indoor unit 9 are connected via the liquid-refrigerant connection pipe 4 and the gas-refrigerant connection pipe 5 to constitute a refrigerant circuit 6.

The air conditioning apparatus 1 illustrated in FIG. 1 includes one indoor unit 9. The air conditioning apparatus 1 may include a plurality of indoor units 9 connected in parallel to the outdoor unit 2 via the liquid-refrigerant connection pipe 4 and the gas-refrigerant connection pipe 5. The air conditioning apparatus 1 may alternatively include a plurality of outdoor units 2. The air conditioning apparatus 1 may alternatively include an outdoor unit 2 and an indoor unit 9 that are integrated with each other.

(1-1) Outdoor Unit

The outdoor unit 2 is installed outside the air conditioning target space. For example, the outdoor unit 2 is installed on the rooftop of a building or near a wall surface of a building.

The outdoor unit 2 mainly includes an accumulator 7, a compressor 8, a four-way switching valve 10, the outdoor heat exchanger 11, an expansion mechanism 12, a liquid-side shutoff valve 13, a gas-side shutoff valve 14, and an outdoor fan 16 (see FIG. 1).

The outdoor unit 2 mainly includes, as refrigerant pipes for connecting various components of the refrigerant circuit 6, a suction pipe 17, a discharge pipe 18, a first gas-refrigerant pipe 19, a liquid-refrigerant pipe 20, and a second gas-refrigerant pipe 21 (see FIG. 1). The suction pipe 17 connects the four-way switching valve 10 and a suction side of the compressor 8. The suction pipe 17 is provided with the accumulator 7. The discharge pipe 18 connects a discharge side of the compressor 8 and the four-way switching valve 10. The first gas-refrigerant pipe 19 connects the four-way switching valve 10 and a gas side of the outdoor heat exchanger 11. The liquid-refrigerant pipe 20 connects a liquid side of the outdoor heat exchanger 11 and the liquid-side shutoff valve 13. The liquid-refrigerant pipe 20 is provided with the expansion mechanism 12. The second gas-refrigerant pipe 21 connects the four-way switching valve 10 and the gas-side shutoff valve 14.

The compressor 8 is configured to suck in a low-pressure refrigerant in the refrigeration cycle, through the suction pipe 17, compress the refrigerant in a compression mechanism (not illustrated), and discharge the compressed refrigerant to the discharge pipe 18.

The four-way switching valve 10 is configured to switch a refrigerant flowing direction, thereby changing a state of the refrigerant circuit 6 between a cooling operation state and a heating operation state. When the refrigerant circuit 6 is in the cooling operation state, the outdoor heat exchanger 11 functions as a radiator (a condenser) for the refrigerant, and an indoor heat exchanger 91 functions as an evaporator for the refrigerant. When the refrigerant circuit 6 is in the heating operation state, the outdoor heat exchanger 11 functions as an evaporator for the refrigerant, and the indoor heat exchanger 91 functions as a condenser for the refrigerant. When the four-way switching valve 10 switches the state of the refrigerant circuit 6 to the cooling operation state, the four-way switching valve 10 causes the suction pipe 17 to communicate with the second gas-refrigerant pipe 21, and causes the discharge pipe 18 to communicate with the first gas-refrigerant pipe 19 (see a solid line in the four-way switching valve 10 illustrated in FIG. 1). When the four-way switching valve 10 switches the state of the refrigerant circuit 6 to the heating operation state, the four-way switching valve 10 causes the suction pipe 17 to communicate with the first gas-refrigerant pipe 19, and causes the discharge pipe 18 to communicate with the

second gas-refrigerant pipe 21 (see a broken line in the four-way switching valve 10 illustrated in FIG. 1).

The outdoor heat exchanger 11 (which is an example of a heat exchanger) is configured to cause the refrigerant flowing therethrough to exchange heat with air (heat source air) in the place where the outdoor unit 2 is installed. A specific description on the outdoor heat exchanger 11 will be given later.

The expansion mechanism 12 is disposed between the outdoor heat exchanger 11 and the indoor heat exchanger 91 in the refrigerant circuit 6. In one or more embodiments, the expansion mechanism 12 is disposed on the liquid-refrigerant pipe 20 between the outdoor heat exchanger 11 and the liquid-side shutoff valve 13. In the air conditioning apparatus 1, the outdoor unit 2 includes the expansion mechanism 12. Alternatively, the indoor unit 9 (to be described later) may include the expansion mechanism 12. The expansion mechanism 12 is configured to adjust a pressure and a flow rate of the refrigerant flowing through the liquid-refrigerant pipe 20. In one or more embodiments, the expansion mechanism 12 is an opening degree-changeable electronic expansion valve. The expansion mechanism 12 may alternatively be a feeler bulb-type expansion valve or a capillary tube.

The accumulator 7 has a gas-liquid separating function of separating the refrigerant, which flows thereto, into the gas refrigerant and the liquid refrigerant. The accumulator 7 also has a surplus refrigerant storing function of storing a surplus of the refrigerant in accordance with, for example, a variation in operation load.

The liquid-side shutoff valve 13 is disposed on a joint between the liquid-refrigerant pipe 20 and the liquid-refrigerant connection pipe 4. The gas-side shutoff valve 14 is disposed on a joint between the second gas-refrigerant pipe 21 and the gas-refrigerant connection pipe 5. The liquid-side shutoff valve 13 and the gas-side shutoff valve 14 are open during the operation of the air conditioning apparatus 1.

The outdoor fan 16 is configured to take heat source air from the outside in a casing (not illustrated) of the outdoor unit 2, supply the heat source air to the outdoor heat exchanger 11, and discharge the air subjected to heat exchange with the refrigerant in the outdoor heat exchanger 11, to the outside of the casing of the outdoor unit 2. The outdoor fan 16 is, for example, a propeller fan.

(1-2) Indoor Unit

The indoor unit 9 is installed in the air conditioning target space. For example, the indoor unit 9 is designed to be embedded in a ceiling. The indoor unit 9 may alternatively be designed to be suspended from a ceiling, hung on a wall, or placed on a floor. Alternatively, the indoor unit 9 may be installed outside the air conditioning target space. For example, the indoor unit 9 may be installed in an attic, a machine chamber, a garage, or the like. In this case, an air passage is provided for supplying air subjected to heat exchange with the refrigerant in the indoor heat exchanger 91, from the indoor unit 9 to the air conditioning target space. The air passage is, for example, a duct.

The indoor unit 9 mainly includes the indoor heat exchanger 91 and an indoor fan 92 (see FIG. 1).

The indoor heat exchanger 91 causes the refrigerant flowing therethrough to exchange heat with the air in the air conditioning target space. The indoor heat exchanger 91 may be of any type. For example, the indoor heat exchanger 91 may be a fin-and-tube heat exchanger that includes a plurality of heat transfer tubes and a plurality of fins (not illustrated). The indoor heat exchanger 91 has a first end connected to the liquid-refrigerant connection pipe 4 via a

refrigerant pipe. The indoor heat exchanger 91 has a second end connected to the gas-refrigerant connection pipe 5 via a refrigerant pipe.

The indoor fan 92 is configured to suck air in the air conditioning target space into a casing (not illustrated) of the indoor unit 9, supply the air to the indoor heat exchanger 91, and blow out the air subjected to heat exchange with the refrigerant in the indoor heat exchanger 91 toward the air conditioning target space. The indoor fan 92 is, for example, a turbo fan. The indoor fan 92 is not limited to a turbo fan, and a fan of any type may be appropriately selected as the indoor fan 92.

(1-3) Control Unit

The control unit 3 is a functional unit configured to control the operations of the various components of the air conditioning apparatus 1.

For example, the control unit 3 includes an outdoor control unit (not illustrated) of the outdoor unit 2 and an indoor control unit (not illustrated) of the indoor unit 9 that are connected to communicate with each other via a transmission line (not illustrated). Each of the outdoor control unit and the indoor control unit includes, for example, a microcomputer and a memory storing various programs for controlling the air conditioning apparatus 1, the programs being executable by the microcomputer. For sake of convenience, FIG. 1 depicts the control unit 3 at a position away from the outdoor unit 2 and the indoor unit 9.

The functions of the control unit 3 are not necessarily achieved by the cooperation of the outdoor control unit and the indoor control unit. For example, the functions of the control unit 3 may be achieved by one of the outdoor control unit and the indoor control unit. Alternatively, some or all the functions of the control unit 3 may be achieved by a control device (not illustrated) different from the outdoor control unit and the indoor control unit.

As illustrated in FIG. 1, the control unit 3 is electrically connected to various components (including the compressor 8, the four-way switching valve 10, the expansion mechanism 12, the outdoor fan 16, and the indoor fan 92) of the outdoor unit 2 and indoor unit 9. The control unit 3 is also electrically connected to various sensors (not illustrated) in the outdoor unit 2 and indoor unit 9. The control unit 3 is capable of communicating with a remote controller (not illustrated) to be operated by a user of the air conditioning apparatus 1.

The control unit 3 starts or stops an operation of the air conditioning apparatus 1 and controls the operations of the various components of the air conditioning apparatus 1, based on, for example, measurement signals from the various sensors and commands from the remote controller (not illustrated).

(2) Configuration of Outdoor Heat Exchanger

Next, a description will be given of a configuration of the outdoor heat exchanger 11 with reference to the drawings.

FIG. 2 is a schematic perspective view of the outdoor heat exchanger 11. FIG. 3 is a partially enlarged view of a heat exchange part 27 (to be described later) of the outdoor heat exchanger 11. FIG. 4 is a schematic diagram of the heat exchange part 27 in which a fin 29 is mounted to a flat tube 28 (which will be described later). FIG. 5 is a schematic configuration diagram of the outdoor heat exchanger 11. In FIG. 5, arrows depicted in the heat exchange part 27 each indicate a flow of the refrigerant during the heating operation (in which the outdoor heat exchanger 11 functions as an evaporator).

In the following, orientations and positions are sometimes described using the terms "upper (up)", "lower (down)", "left", "right", "front (front face)", and "rear (rear face)". These orientations and positions are defined by the arrows depicted in FIG. 2 unless otherwise specified. It should be noted that the terms representing the orientations and positions are used for sake of convenience of the description and therefore do not specify the orientation and position of the entire outdoor heat exchanger 11 and the orientation and position of each component of the outdoor heat exchanger 11 unless otherwise specified.

The outdoor heat exchanger 11 is configured to cause the refrigerant flowing therethrough to exchange heat with air.

The outdoor heat exchanger 11 mainly includes a distributor 22, a flat tube group 28G that includes the plurality of flat tubes 28, the plurality of fins 29, a liquid header 40, and a gas header 70 (which is an example of a header) (see FIGS. 4 and 5). In one or more embodiments, the distributor 22, the flat tubes 28, the fins 29, the liquid header 40, and the gas header 70 are each made of aluminum or an aluminum alloy.

As will be described later, the flat tubes 28 and the fins 29 fixed to the flat tubes 28 constitute the heat exchange part 27 (see FIGS. 2 and 3). The outdoor heat exchanger 11 includes the heat exchange part 27 placed in a line; therefore, the configuration of the outdoor heat exchanger 11 is different from that in which the flat tubes 28 are arranged in the air flowing direction. In the outdoor heat exchanger 11, air flows through an air flow path defined by each flat tube 28 and the corresponding fin 29 in the heat exchange part 27. The outdoor heat exchanger 11 causes the refrigerant flowing through each flat tube 28 to exchange heat with the air flowing through the corresponding air flow path. The heat exchange part 27 is divided into a first heat exchange part 27a, a second heat exchange part 27b, a third heat exchange part 27c, a fourth heat exchange part 27d, and a fifth heat exchange part 27e arranged in the up-and-down direction (see FIG. 2).

(2-1) Distributor

The distributor 22 is configured to divert the refrigerant. The distributor 22 is also configured to merge the diverted refrigerants into one. The liquid-refrigerant pipe 20 is connected to the distributor 22. The distributor 22 includes a plurality of distributor tubes 22a to 22e. The distributor 22 has a function of diverting the refrigerant flowing thereto through the liquid-refrigerant pipe 20 into the distributor tubes 22a to 22e and leading the diverted refrigerants to spaces defined in the liquid header 40. The distributor 22 also has a function of merging the refrigerants flowing thereto from the liquid header 40 via the distributor tubes 22a to 22e into one and leading the refrigerant toward the liquid-refrigerant pipe 20.

(2-2) Flat Tube Group

The flat tube group 28G is an example of a heat transfer tube group. The flat tube group 28G includes the plurality of flat tubes 28 (each of which is an example of a heat transfer tube) as a plurality of heat transfer tubes. As illustrated in FIG. 3, each of the flat tubes 28 is a flat heat transfer tube having upper and lower flat faces 28a each serving as a heat transfer face. As illustrated in FIG. 3, each of the flat tubes 28 includes a plurality of refrigerant passages 28b through which the refrigerant flows. Each of the flat tubes 28 is, for example, a flat porous pipe including a plurality of refrigerant passages 28b each allowing the refrigerant to flow therethrough and having a small passage sectional area. In one or more embodiments, the refrigerant passages 28b are arranged in the air flowing direction. A maximum width of

each of the flat tubes 28 in cross section perpendicular to the refrigerant passages 28b may be 70% or more and alternatively be 85% or more of the outer diameter of the main gas-refrigerant pipe connection portion 19a.

As illustrated in FIG. 5, in the outdoor heat exchanger 11, the flat tubes 28 extend between the liquid header 40 and the gas header 70 in a horizontal direction. Moreover, the flat tubes 28 are arranged up and down in multiple tiers. In one or more embodiments, the flat tubes 28 between the liquid header 40 and the gas header 70 are bent at two points, so that the heat exchange part 27 including the flat tubes 28 has a substantially "U" shape as seen in plan view (see FIG. 2). The flat tubes 28 each have a portion that extends in a front-and-rear direction (which is an example of a first direction) and is connected to the gas header 70, and a portion that extends in the front-and-rear direction and is connected to the liquid header 40. In one or more embodiments, the flat tubes 28 are arranged up and down at certain spacings.

(2-3) Fin

The fins 29 are used for increasing a heat transfer area of the outdoor heat exchanger 11. The fins 29 each have a plate shape extending in a direction in which the flat tubes 28 are arranged in tiers. The outdoor heat exchanger 11 is used in the state in which the flat tubes 28 extending in the horizontal direction are arranged in the up-and-down direction. Therefore, the fins 29 extend in the up-and-down direction with the outdoor heat exchanger 11 installed in the outdoor unit 2.

As illustrated in FIG. 4, each of the fins 29 has a plurality of cutouts 29a extending in such a direction that the flat tubes 28 are inserted into the cutouts 29a. The cutouts 29a extend in the direction in which the fins 29 extend and in a direction orthogonal to a thickness direction of each fin 29. The cutouts 29a in each fin 29 extend in the horizontal direction with the outdoor heat exchanger 11 installed in the outdoor unit 2. The cutouts 29a in each fin 29 each have a shape that is almost equal to an outer cross-sectional shape of each flat tube 28. In each fin 29, a spacing between adjacent two of the cutouts 29a corresponds to the spacing between adjacent two of the flat tubes 28. In the outdoor heat exchanger 11, the fins 29 are arranged in the direction in which the flat tubes 28 extend. In each of the fins 29, the flat tubes 28 are respectively inserted into the cutouts 29a, so that a plurality of air flow paths, through which air flows, are defined between adjacent two of the flat tubes 28.

Each of the fins 29 has a communicating portion 29b disposed upstream or downstream of the flat tubes 28 in the air flowing direction. The communicating portions 29b extend in the up-and-down direction. In one or more embodiments, the communicating portions 29b of the fins 29 are located on the windward side with respect to the flat tubes 28.

(2-4) Gas Header, Liquid Header

The liquid header 40 and the gas header 70 each have a hollow shape.

As illustrated in FIG. 5, the liquid header 40 is connected to a first end of each flat tube 28, and the gas header 70 is connected to a second end of each flat tube 28. The outdoor heat exchanger 11 is disposed in the casing (not illustrated) of the outdoor unit 2 such that an axial direction of each of the liquid header 40 and the gas header 70 each having a substantially columnar shape is approximately parallel to a vertical direction. In one or more embodiments, as illustrated in FIG. 2, the heat exchange part 27 of the outdoor heat exchanger 11 has the "U" shape as seen in plan view. The liquid header 40 is disposed near the front left corner of

the casing (not illustrated) of the outdoor unit 2 (see FIG. 2). The gas header 70 is disposed near the front right corner of the casing (not illustrated) of the outdoor unit 2 (see FIG. 2).

(2-4-1) Liquid Header

5 The liquid header 40 has a longitudinal direction parallel to the up-and-down direction.

The liquid header 40 has a liquid-side internal space 23 divided into a plurality of sub-spaces 23a to 23e by a plurality of partition plates 24 (see FIG. 5).

10 The sub-spaces 23a to 23e are arranged in the up-and-down direction. The sub-spaces 23a to 23e of the liquid-side internal space 23 divided by the partition plates 24 are in a non-communicating state in the liquid header 40.

The distributor tubes 22a to 22e of the distributor 22 are 15 respectively connected to the sub-spaces 23a to 23e. During the cooling operation, when the refrigerant flows into each of the sub-spaces 23a to 23e, the refrigerants then flow through the distributor tubes 22a to 22e. The refrigerants are then merged into one at the distributor 22. During the 20 heating operation, when the refrigerant flows into the distributor 22, the distributor 22 supplies the diverted refrigerants to the sub-spaces 23a to 23e.

(2-4-2) Gas Header

The gas header 70 has a longitudinal direction parallel to 25 the up-and-down direction (which is an example of a second direction).

The gas header 70 has a single space. The gas header 70 has a gas-side internal space 25 that is not divided by partition plates, unlike the liquid-side internal space 23 divided into the sub-spaces 23a to 23e arranged up and down in the liquid header 40.

The gas header 70 is connected to a main gas-refrigerant pipe connection portion 19a (which is an example of a first pipe and a gas pipe) and a branch gas-refrigerant pipe 35 connection portion 19b (which is an example of a first pipe and a gas pipe). The main gas-refrigerant pipe connection portion 19a and the branch gas-refrigerant pipe connection portion 19b each constitute a gas header 70-side end of the first gas-refrigerant pipe 19 (which is an example of a first pipe and a gas pipe) (see FIG. 5). The main gas-refrigerant pipe connection portion 19a has an outer diameter that is not limited. For example, the outer diameter of the main gas-refrigerant pipe connection portion 19a may be 3 times or more larger and alternatively 5 times or more larger than the 40 outer diameter of the branch gas-refrigerant pipe connection portion 19b.

The main gas-refrigerant pipe connection portion 19a has a first end connected to the gas header 70 to communicate with the gas-side internal space 25 (which is an example of a space defined by a first wall and a second wall) at an intermediate position of the gas header 70 in a height direction.

The branch gas-refrigerant pipe connection portion 19b has a first end connected to the gas header 70 to communicate with the gas-side internal space 25 at a position near a lower end of the gas header 70 in the height direction. The branch gas-refrigerant pipe connection portion 19b has a second end connected to the main gas-refrigerant pipe connection portion 19a. The branch gas-refrigerant pipe connection portion 19b is smaller in inner diameter than the main gas-refrigerant pipe connection portion 19a. The branch gas-refrigerant pipe connection portion 19b is connected to the gas header 70 at a position below the main gas-refrigerant pipe connection portion 19a. A refrigerating machine oil retained near the lower end of the gas header 70 is thus drawn into the main gas-refrigerant pipe connection portion 19a.

11

(3) Flow of Refrigerant in Outdoor Heat Exchanger

In a case where the air conditioning apparatus 1 carries out the heating operation so that the outdoor heat exchanger 11 functions as an evaporator for the refrigerant, the refrigerant in the gas-liquid two-phase state flows into the distributor 22 through the liquid-refrigerant pipe 20. The diverted refrigerants then flow through the distributor tubes 22a to 22e and flow into the sub-spaces 23a to 23e of the liquid-side internal space 23 in the liquid header 40. Specifically, the refrigerant flowing through the distributor tube 22a flows into the sub-space 23a, the refrigerant flowing through the distributor tube 22b flows into the sub-space 23b, the refrigerant flowing through the distributor tube 22c flows into the sub-space 23c, the refrigerant flowing through the distributor tube 22d flows into the sub-space 23d, and the refrigerant flowing through the distributor tube 22e flows into the sub-space 23e. When the refrigerants flow into the sub-spaces 23a to 23e of the liquid-side internal space 23, then the refrigerants flow through the flat tubes 28 respectively connected to the sub-spaces 23a to 23e. The refrigerants flowing through the flat tubes 28 evaporate by heat exchange with air, so that the gas-phase refrigerants flow into the gas-side internal space 25 in the gas header 70. The gas-phase refrigerants are thus merged into one.

In a case where the air conditioning apparatus 1 carries out the cooling operation or a defrosting operation, the refrigerant flows through the refrigerant circuit 6 in the opposite direction to that during the heating operation. Specifically, the high-temperature gas-phase refrigerant flows into the gas-side internal space 25 in the gas header 70 through the main gas-refrigerant pipe connection portion 19a and branch gas-refrigerant pipe connection portion 19b of the first gas-refrigerant pipe 19. The refrigerant is diverted in the gas-side internal space 25 in the gas header 70, and the diverted refrigerants then flow into the flat tubes 28. The refrigerants flowed into the flat tubes 28 then flow through the flat tubes 28 and flow into the sub-spaces 23a to 23e of the liquid-side internal space 23 in the liquid header 40. The refrigerants flowed into the sub-spaces 23a to 23e of the liquid-side internal space 23 are then merged into one in the distributor 22. The merged refrigerant then flows into the liquid-refrigerant pipe 20.

(4) Details of Gas Header

FIG. 6 is an external view of the gas header 70 to which the main gas-refrigerant pipe connection portion 19a is connected as seen in side view. FIG. 7 is a sectional view of the gas header 70 as seen in plan view. FIG. 8 is a sectional view of the gas header 70 to which the main gas-refrigerant pipe connection portion 19a and the flat tubes 28 are connected as seen in plan view.

FIG. 9 is a schematic diagram of a rear side of a first member 71. FIG. 10 is a schematic diagram of a rear side of a third member 73. FIG. 11 is a schematic diagram of a rear side of a second member 72. FIG. 12 is an external perspective view of the second member 72. FIG. 13 is a schematic diagram of a rear side of a fourth member 74. FIG. 14 is a projection view of a positional relationship among openings in a case where the first member 71 is seen from its rear side.

The gas header 70 includes the first member 71, the second member 72, the third member 73, the fourth member 74, an upper-end cover member (not illustrated), and a lower-end cover member (not illustrated). In the gas header 70, the first member 71, the second member 72, the third

12

member 73, the fourth member 74, the upper-end cover member, and the lower-end cover member are joined together by brazing.

The gas header 70 has a substantially quadrangle outer shape as seen in plan view, and one of the four sides is connected to the flat tubes 28.

(4-1) First Member

The first member 71 mainly forms an outer shape of the gas header 70 in conjunction with the fourth member 74 (to be described later). Preferably, the first member 71 has on its surface a cladding layer containing a brazing material.

The first member 71 includes a flat tube connection plate 71a, a first outer wall 71b, a second outer wall 71c, a first claw 71d, and a second claw 71e.

In one or more embodiments, the first member 71 is formed of a sheet metal, which is obtained by rolling, by bending the sheet metal in the longitudinal direction of the gas header 70 although the method of forming the first member 71 is not limited thereto. In this case, the first member 71 has a uniform thickness that is a first thickness.

The flat tube connection plate 71a (which is an example of a first portion) has a flat plate shape expanding in the up-and-down direction and in the left-and-right direction.

The flat tube connection plate 71a has a plurality of flat tube connection openings 71x (each of which is an example of a first opening) arranged in the up-and-down direction. Each of the flat tube connection openings 71x is bored through the flat tube connection plate 71a in the thickness direction. The flat tubes 28 are inserted into the flat tube connection openings 71x such that the first ends thereof fully pass through the flat tube connection openings 71x, and are joined to the flat tube connection openings 71x by brazing. In the state in which the flat tubes 28 are joined to the flat tube connection openings 71x by brazing, the entire inner peripheral face of each flat tube connection opening 71x is in contact with the entire outer peripheral face of the corresponding flat tube 28. The first thickness, which is the thickness of the first member 71 including the flat tube connection plate 71a is relatively thin and is, for example, within a range from about 1.0 mm to about 2.0 mm. This configuration therefore reduces a length of the inner peripheral face of each flat tube connection opening 71x in the thickness direction. In inserting each flat tube 28 into the corresponding flat tube connection opening 71x before joining the flat tube 28 and the flat tube connection opening 71x together by brazing, this configuration reduces friction between the inner peripheral face of the flat tube connection opening 71x and the outer peripheral face of the flat tube 28, which facilitates the inserting work.

The first outer wall 71b (which is an example of a wall surface portion) has a planar shape and extends from a front face of a left end of the flat tube connection plate 71a (i.e., the inner side of the outdoor unit 2, the side of the liquid header 40) toward the first gas-refrigerant pipe 19 along the first inner wall 72b (to be described later).

The second outer wall 71c (which is an example of a wall surface portion) has a planar shape and extends from a front face of a right end of the flat tube connection plate 71a (i.e., the outer side of the outdoor unit 2, the side opposite to the liquid header 40) toward the first gas-refrigerant pipe 19 along the second inner wall 72c (to be described later).

The first claw 71d (which is an example of a claw) protrudes rightward from a front end of the first outer wall 71b. The second claw 71e (which is an example of a claw) protrudes leftward from a front end of the second outer wall 71c.

In a state before the second member 72, the third member 73, and the fourth member 74 are placed inside the first member 71 as seen in plan view, the first claw 71d extends on the extension of the first outer wall 71b, and the second claw 71e extends on the extension of the second outer wall 71c. In the state in which the second member 72, the third member 73, and the fourth member 74 are placed inside the first member 71 as seen in plan view, the first claw 71d and the second claw 71e are bent to come close to each other. As a result, the second member 72, the third member 73, and the fourth member 74 are fixed together by crimping with the first member 71. In this state, the first member 71, the second member 72, the third member 73, and the fourth member 74 are joined together by brazing in, for example, a furnace and are thus completely fixed together.

(4-2) Third Member

The third member 73 has a flat plate shape expanding in the up-and-down direction and the left-and-right direction. The third member 73 is stacked on the flat tube connection plate 71a of the first member 71 in contact with a surface of the flat tube connection plate 71a to which the first gas-refrigerant pipe 19 is connected. The third member 73 is similar in left-to-right length to the flat tube connection plate 71a of the first member 71 excluding two ends of the flat tube connection plate 71a.

Preferably, the third member 73 has on its surface a cladding layer containing a brazing material.

The third member 73 includes an internal plate 73a and a plurality of internal openings 73x.

The internal plate 73a has a flat plate shape expanding in the up-and-down direction and the left-and-right direction.

The internal openings 73x are arranged in the up-and-down direction and are bored through the internal plate 73a in the thickness direction.

The internal openings 73x in the third member 73 each are larger than the flat tube connection openings 71x in the flat tube connection plate 71a of the first member 71. In the state in which the third member 73 is stacked on the flat tube connection plate 71a of the first member 71, an outer edge of each internal opening 73x in the third member 73 is located outward of an outer edge of the corresponding flat tube connection opening 71x in the flat tube connection plate 71a of the first member 71 in the stacking direction of the members, more specifically in the front-and-rear direction. This configuration suppresses occurrence of a situation in which the brazing material moves by a capillary phenomenon in joining the members together by brazing to close the refrigerant passages 28b in the flat tubes 28. From this point of view, upper and lower portions of the outer edge of each internal opening 73x in the third member 73 may be separated from upper and lower portions of the outer edge of the corresponding flat tube connection opening 71x in the flat tube connection plate 71a by 2 mm or more, preferably 3 mm or more.

(4-3) Second Member

The second member 72 is disposed between the flat tube connection plate 71a of the first member 71 and the main gas-refrigerant pipe connection portion 19a in the front-and-rear direction. The second member 72 has a substantially "U" shape as seen in plan view.

The gas-side internal space 25 described above is defined inside the second member 72, more specifically in the space surrounded by the second member 72, the third member 73, and the ends of the flat tubes 28.

Preferably, the second member 72 has a maximum thickness larger than the thickness of the first member 71. This configuration enables pressure resistance strength enhancement to the gas header 70.

Preferably, the second member 72 is obtained by extrusion molding in which the longitudinal direction of the gas header 70 is defined as an extruding direction. However, the method of forming the second member 72 is not limited thereto. The extrusion molding facilitates formation of portions that are different in thickness from one another. A thick sheet metal is relatively expensive. Therefore, cost reduction is achieved in such a manner that a thick second member 72 is formed by extrusion molding. The second member 72 formed by extrusion molding may have no cladding layer containing a brazing material.

The second member 72 includes a first inner wall 72b, a second inner wall 72c, a coupling portion 72a, a first protrusion 72d, a second protrusion 72e, a first edge 72f, and a second edge 72g.

The coupling portion 72a opposes to a main gas-refrigerant pipe connection portion 19a-side surface of the third member 73. The coupling portion 72a has a plate shape expanding in the up-and-down direction and the left-and-right direction. The coupling portion 72a is located on the side of the main gas-refrigerant pipe connection portion 19a in the gas header 70. The coupling portion 72a has an internal gas pipe connection opening 72x to which the end of the main gas-refrigerant pipe connection portion 19a is connected. The internal gas pipe connection opening 72x is bored through the coupling portion 72a in the thickness direction. The coupling portion 72a has an opening (not illustrated) to which the end of the branch gas-refrigerant pipe connection portion 19b is connected. This opening is bored through the coupling portion 72a in the thickness direction.

The first inner wall 72b (which is an example of a first wall) has a planar shape extending from the left end of the coupling portion 72a (i.e., the inner side of the outdoor unit 2, the side closer to the liquid header 40) toward the rear side from which the flat tubes 28 protrude. The first inner wall 72b has a left face that is in surface contact with a right face of the first outer wall 71b of the first member 71.

The second inner wall 72c (which is an example of a second wall) has a planar shape extending from the right end of the coupling portion 72a (i.e., the outer side of the outdoor unit 2, the side opposite to the liquid header 40) toward the rear side from which the flat tubes 28 protrude. The second inner wall 72c has a right face that is in surface contact with a left face of the second outer wall 71c of the first member 71.

The first inner wall 72b opposes to the second inner wall 72c. A front end of the first inner wall 72b particularly opposes to a front end of the second inner wall 72c.

The coupling portion 72a, the first inner wall 72b, and the second inner wall 72c each have a thickness larger than the thickness of the first member 71 which may be 1.5 times or more, preferably twice or more larger than the thickness of the first member 71.

The first inner wall 72b and the second inner wall 72c each may have a length in the protruding direction of the flat tubes 28 (the front-and-rear direction), 3 times or more, preferably 5 times or more larger than a length of the coupling portion 72a in the protruding direction of the flat tubes 28 (the front-and-rear direction). However, these lengths are not limited thereto.

The coupling portion 72a couples the first inner wall 72b to the second inner wall 72c. Specifically, the coupling

portion **72a** couples the front end (the main gas-refrigerant pipe connection portion **19a**-side end) of the first inner wall **72b** to the front end (the main gas-refrigerant pipe connection portion **19a**-side end) of the second inner wall **72c**. The coupling portion **72a** extends in the left-and-right direction when the gas header **70** is seen in plan view. The left-and-right direction is an example of a third direction. Preferably, the third direction is orthogonal to both the first direction and the second direction. More preferably, the first direction, the second direction, and the third direction are orthogonal to one another.

The first edge **72f** is located behind the first inner wall **72b**. That is, the first edge **72f** is located closer to the flat tubes **28** than the first inner wall **72b** is. The first edge **72f** has a left face that is flush with a left face of the first inner wall **72b** and is in surface contact with a right face of the first outer wall **71b** of the first member **71**. The first edge **72f** has a rear end that is in contact with a front face of the third member **73**. The first edge **72f** is smaller in thickness (width in the left-and-right direction) than the first inner wall **72b**. A contact portion between the first edge **72f** and the front face of the third member **73** is located leftward of the flat tubes **28** and leftward of left ends of the internal openings **73x** (each of which is an example of a second opening) in the third member **73**.

The second edge **72g** is located behind the second inner wall **72c**. That is, the second edge **72g** is located closer to the flat tubes **28** than the second inner wall **72c** is. The second edge **72g** has a right face that is flush with a right face of the second inner wall **72c** and is in surface contact with a left face of the second outer wall **71c** of the first member **71**. The second edge **72g** has a rear end that is in contact with the front face of the third member **73**. The second edge **72g** is smaller in thickness (width in the left-and-right direction) than the second inner wall **72c**. A contact portion between the second edge **72g** and the front face of the third member **73** is located rightward of the flat tubes **28** and rightward of right ends of the internal openings **73x** in the third member **73**.

As seen in plan view, a length between the first edge **72f** and the second edge **72g** is larger than a width of each flat tube **28**, larger than a width of each flat tube connection opening **71x** in the first member **71**, and larger than a width of each internal opening **73x** in the third member **73**. The first edge **72f** and the second edge **72g** each extend from the upper end to the lower end of the gas header **70**.

The first protrusion **72d** protrudes rightward (toward the second inner wall **72c**) from the rear end of the first inner wall **72b**, that is, a portion forward of the first edge **72f**. The first protrusion **72d** extends from the upper end to the lower end of the gas header **70**. The first protrusion **72d** has a right end that is located rightward of the left ends of the internal openings **73x** in the third member **73** and rightward of the left ends of the flat tubes **28**. The first protrusion **72d** is located closer to the flat tubes **28** with respect to a center of the second member **72** in the front-and-rear direction.

The second protrusion **72e** protrudes leftward (toward the first inner wall **72b**) from the rear end of the second inner wall **72c**, that is, a portion forward of the second edge **72g**. The second protrusion **72e** extends from the upper end to the lower end of the gas header **70**. The second protrusion **72e** has a left end located leftward of the right ends of the internal openings **73x** in the third member **73** and leftward of the right ends of the flat tubes **28**. The second protrusion **72e** is located closer to the flat tubes **28** with respect to the center of the second member **72** in the front-and-rear direction.

A minimum distance between the first protrusion **72d** and the second protrusion **72e** (a distance between the first protrusion **72d** and the second protrusion **72e** in the left-and-right direction) is shorter than a maximum width of each flat tube **28** in section perpendicular to the refrigerant passage **28b**. With this configuration, when the flat tubes **28** are inserted into the gas header **70**, the first protrusion **72d** and the second protrusion **72e** define the degree of insertion of each flat tube **28**. This configuration therefore suppresses a reduction in size of the gas-side internal space **25** owing to the excessively large degree of insertion of each flat tube **28**. With this configuration, moreover, the first protrusion **72d** and the second protrusion **72e** bring the positions of the ends of the flat tubes **28** into alignment in the gas header **70**.

(4-4) Fourth Member

The fourth member **74** has a flat plate shape expanding in the up-and-down direction and the left-and-right direction. The fourth member **74** is stacked on the second member **72** in contact with a front face of the coupling portion **72a**. The fourth member **74** is similar in left-to-right length to the third member **73**. The fourth member **74** is also similar in left-to-right length to the flat tube connection plate **71a** of the first member **71** excluding the two ends of the flat tube connection plate **71a**.

Preferably, the fourth member **74** has on its surface a cladding layer containing a brazing material. The fourth member **74** is a plate-shaped member; therefore, the cladding layer containing the brazing material is formed on the surface of the fourth member **74** with ease. Therefore, for example, as in the case where the second member **72** is formed by extrusion molding, even in a case where the second member **72** has no cladding layer containing a brazing material, the second member **72** is joined to the other members by brazing with the brazing material on the fourth member **74**.

The fourth member **74** includes an external plate **74a** and has an external gas pipe connection opening **74x**.

The external plate **74a** has a flat plate shape expanding in the up-and-down direction and the left-and-right direction.

The external gas pipe connection opening **74x** is bored through the external plate **74a** in the thickness direction, and the end of the main gas-refrigerant pipe connection portion **19a** is connected to the external gas pipe connection opening **74x**.

The external plate **74a** has in its lower side an opening (not illustrated) to which the end of the branch gas-refrigerant pipe connection portion **19b** is connected. This opening is bored through the external plate **74a** in the thickness direction.

The main gas-refrigerant pipe connection portion **19a** and the branch gas-refrigerant pipe connection portion **19b** thus communicate with an inner face of the flat tube connection plate **71a** of the first member **71** via the gas-side internal space **25** defined by the external gas pipe connection opening **74x**, the internal gas pipe connection opening **72x**, the first inner wall **72b**, and the second inner wall **72c**.

The fourth member **74** has a front face that is crimped in contact with the first claw **71d** and second claw **71e** of the first member **71**.

(5) Features of One or More Embodiments

(5-1)

In the gas header **70** of the outdoor heat exchanger **11** according to one or more embodiments, the first inner wall **72b** of the second member **72** extends rearward (in the protruding direction of the flat tubes **28**) from the left end of

the coupling portion 72a, and the second inner wall 72c of the second member 72 extends rearward from the right end of the coupling portion 72a. With this configuration, the gas-side internal space 25 is secured wide without additional members, by simply extending the first inner wall 72b and the second inner wall 72c. With this configuration, the gas refrigerant passing through the gas-side internal space 25 is less susceptible to pressure loss.

The space in the header can also be widened in such a manner that multiple plate-shaped members each having an opening are stacked on top of each other. This case however results in an increase in parts count. The space in the header can also be secured wide in such a manner that openings are bored by punching or the like in a thick plate-shaped member. This case however makes it difficult to perform punching because of the thick plate-shaped member. In contrast to this, the second member 72 of the gas header 70 according to one or more embodiments is a single member formed by extrusion molding. This configuration therefore reduces a parts count for securing the gas-side internal space 25 wide, without a problem accompanied with the punching or the like.

In one or more embodiments, the first inner wall 72b and the second inner wall 72c extend in the protruding direction of the flat tubes 28 in order to secure the gas-side internal space 25 wide. However, the first inner wall 72b and the second inner wall 72c are coupled together by the coupling portion 72a, and the coupling portion 72a, the first inner wall 72b, and the second inner wall 72c are integrated. This configuration enables strength enhancement to the second member 72 and enables pressure resistance strength enhancement to the gas header 70.

The coupling portion 72a is particularly provided for coupling the front end of the first inner wall 72b to the front end of the second inner wall 72c. This case secures the gas-side internal space 25 wide with ease as compared with a case where the coupling portion 72a couples any portion of the first inner wall 72b in the front-and-rear direction, excluding the two ends of the first inner wall 72b in the front-and-rear direction, to any portion of the second inner wall 72c in the front-and-rear direction, excluding the two ends of the second inner wall 72c in the front-and-rear direction.

(5-2)

In a known cylindrical gas header, it has been necessary to deeply insert a flat tube as a flat-shaped heat transfer tube into the gas header in order to cause the entire end of the flat tube to be located inside the cylindrical gas header. Consequently, unnecessary spaces, where a refrigerant is retained, are defined above and below the ends of the flat tube in the cylindrical gas header. The unnecessary spaces may reduce a flow velocity of the refrigerant in the header. This tendency becomes remarkable as a width of the flat tube is larger.

In contrast to this, in the gas header 70 of the outdoor heat exchanger 11 according to one or more embodiments, the flat tube connection plate 71a of the first member 71 and the third member 73 each have a plate shape. In addition, the flat tubes 28 are inserted perpendicularly to the flat tube connection plate 71a of the first member 71 and the third member 73. The first outer wall 71b and the second outer wall 71c extend perpendicularly from the left and right ends of the flat tube connection plate 71a of the first member 71, respectively. The first inner wall 72b and the second inner wall 72c of the second member 72 are joined perpendicularly to the left and right ends of the third member 73, respectively.

With this configuration, in the gas header 70 of the outdoor heat exchanger 11 according to one or more embodiments, an unnecessary space, where a refrigerant is retained, is reduced at a position around the end of each flat tube 28. This configuration reduces a pressure loss of the gas refrigerant flowing through the gas header 70, and suppresses a reduction in flow velocity of the refrigerant in the gas header 70.

(5-3)

10 In the gas header 70 of the outdoor heat exchanger 11 according to one or more embodiments, the first member 71 including the flat tube connection plate 71a is relatively thin. In inserting each flat tube 28 into the corresponding flat tube connection opening 71x before joining the flat tube 28 and 15 the flat tube connection opening 71x together by brazing, this configuration reduces friction between the inner peripheral face of the flat tube connection opening 71x and the outer peripheral face of the flat tube 28, which facilitates the inserting work.

20 Even if the first member 71 including the flat tube connection plate 71a is thin, the third member 73 is stacked on the flat tube connection plate 71a in the thickness direction. This configuration enables pressure resistance strength enhancement to the portion of the gas header 70 on 25 the side to which the flat tubes 28 are connected.

In addition, the outer edge of each internal opening 73x in the third member 73 is located outward of the outer edge of the corresponding flat tube connection opening 71x in the flat tube connection plate 71a of the first member 71. At the 30 time of brazing, therefore, even if the brazing material between the flat tube connection openings 71x in the flat tube connection plate 71a and the flat tubes 28 overflows toward the ends of the flat tubes 28, the overflowing brazing material flows into the spaces in the internal openings 73x in the third member 73, the spaces being located outside the flat tubes 28. This configuration therefore suppresses occurrence of a situation in which the refrigerant passages 28b in the flat tubes 28 are filled with the brazing material.

(5-4)

40 In the gas header 70 of the outdoor heat exchanger 11 according to one or more embodiments, the minimum distance between the first protrusion 72d and the second protrusion 72e (a distance between the first protrusion 72d and the second protrusion 72e in the left-and-right direction) 45 of the second member 72 is shorter than the maximum width of each flat tube 28 in section perpendicular to the refrigerant passage 28b. This configuration therefore defines the degree of insertion of each flat tube 28 in the gas header 70.

The first protrusion 72d and the second protrusion 72e 50 that define the degree of insertion of each flat tube 28 are located closer to the flat tubes 28 with respect to the center of the second member 72 in the front-and-rear direction. This configuration therefore secures the gas-side internal space 25 sufficiently wide.

(6) Modifications

(6-1) Modification A

In the foregoing embodiments, with regard to the second member 72 of the gas header 70 of the outdoor heat exchanger 11, the coupling portion 72a couples the end of the first inner wall 72b to the end of the second inner wall 72c.

In place of this, for example, a second member 172 65 illustrated in FIGS. 15 and 16 may be used as a second member of the gas header 70 of the outdoor heat exchanger 11. FIG. 15 is a sectional view of the gas header 70 to which

19

the main gas-refrigerant pipe connection portion **19a** and the flat tubes **28** are connected as seen in plan view. FIG. 16 is a projection view of a positional relationship among openings in a case where the second member **172** is seen from its rear side.

The second member **172** includes a coupling portion **172a** instead of the coupling portion **72a** of the second member **72** according to the foregoing embodiments. The coupling portion **172a** couples a portion between the ends of the first inner wall **72b** in the front-and-rear direction (the protruding direction of the flat tubes **28**) to a portion between the ends of the second inner wall **72c** in the front-and-rear direction (the protruding direction of the flat tubes **28**). As described above, the coupling portion **172a** couples the first inner wall **72b** and the second inner wall **72c** at the portions different from the ends. This configuration therefore enables structural strength enhancement to the second member **172**.

The coupling portion **172a** has a plate shape expanding in the up-and-down direction and the left-and-right direction. The coupling portion **172a** has a plurality of internal gas pipe connection openings **172x** arranged in the up-and-down direction. The internal gas pipe connection openings **172x** are formed corresponding to the respective flat tubes **28**. The internal gas pipe connection openings **172x** are larger in size in the up-and-down direction than the flat tubes **28** and the flat tube connection openings **71x** in the first member **71**. On the other hand, the internal gas pipe connection openings **172x** are smaller in size in the width direction (the left-and-right direction) than the flat tubes **28** and the flat tube connection openings **71x** in the first member **71**. This configuration thus defines the degree of insertion of each flat tube **28**. Since an edge of each internal gas pipe connection opening **172x** is used for defining the degree of insertion of the corresponding flat tube **28**, the second member **72** does not necessarily include the first protrusion **72d** and the second protrusion **72e** in the foregoing embodiments.

(6-2) Modification B

In the foregoing embodiments, the gas header **70** includes the third member **73** and the fourth member **74**.

In place of this, for example, a gas header **70** illustrated in FIG. 17 may not include one of or both the third member **73** and the fourth member **74** in the foregoing embodiments.

In this case, increasing the thickness of the flat tube connection plate **71a** of the first member **71** secures pressure resistance strength.

Although the present disclosure has been described with respect to only a limited number of embodiments, those skilled in the art, having benefit of this disclosure, will appreciate that various other embodiments may be devised without departing from the scope of the present disclosure. Accordingly, the scope of the present disclosure should be limited only by the attached claims.

 The invention claimed is:
 1. A heat exchanger connected to a first pipe through which a refrigerant flows, the heat exchanger comprising:
 heat transfer tubes extending in a first direction; and
 a header connected to the heat transfer tubes, wherein
 the header includes:
 a first member including a first portion connected to the
 heat transfer tubes; and
 a second member disposed between the first pipe and
 the first portion; and
 a third member disposed to face a side of the first
 portion of the first member where the second mem-
 ber is disposed,
 the second member includes:
 a first wall and a second wall that each extend in the
 first direction; and
 a coupling portion that couples the first wall to the
 second wall,
 the first pipe communicates with each heat transfer tube
 through a space delimited by the first wall and the
 second wall,
 a longitudinal direction of the first wall and a longitudinal
 direction of the second wall in a section view along the
 longitudinal direction of the header are in the first
 direction,
 the first wall, the second wall, and the coupling portion are
 plates,
 the coupling portion, the first wall, and the second wall
 each have a thickness greater than a thickness of the
 first member,
 the first portion has first openings that accommodate the
 heat transfer tubes,
 the third member has second openings that accommodate
 the heat transfer tubes, and
 each first opening has a portion overlapping the respective
 second opening when viewed in the first direction.
 2. The heat exchanger according to claim 1, wherein
 the coupling portion couples an end of the first wall in the
 first direction to an end of the second wall in the first
 direction.
 3. The heat exchanger according to claim 1, wherein
 the coupling portion couples a portion of the first wall to
 a portion of the second wall,
 the portion of the first wall is different from two ends of
 the first wall in the first direction, and
 the portion of the second wall is different from two ends
 of the second wall in the first direction.

21

4. The heat exchanger according to claim 1, wherein the first portion is planar.
5. The heat exchanger according to claim 1, wherein the second member includes:
- a first protrusion protruding from the first wall toward the second wall; and
  - a second protrusion protruding from the second wall toward the first wall,
- the first and second protrusions are disposed closer to the heat transfer tubes than the coupling portion, and a minimum distance between the first protrusion and the second protrusion is shorter than a maximum width of each heat transfer tube in a section view perpendicular to the heat transfer tubes.
6. The heat exchanger according to claim 5, wherein the coupling portion couples a portion of the first wall to a portion of the second wall,
- the portion of the first wall is disposed closer to the first pipe than a center of the first wall in the first direction, the portion of the second wall is disposed closer to the first pipe than a center of the second wall in the first direction,
- the first protrusion is disposed closer to the heat transfer tubes than the center of the first wall in the first direction, and
- the second protrusion is disposed closer to the heat transfer tubes than the center of the second wall in the first direction.
7. The heat exchanger according to claim 5, wherein the first wall includes a first edge disposed on a side of the first protrusion disposed closer to the heat transfer tubes than the coupling portion,
- the second wall includes a second edge disposed on a side of the second protrusion disposed closer to the heat transfer tubes than the coupling portion,
- a thickness of the first edge is less than a thickness of the first wall disposed between the first protrusion and the coupling portion, and
- a thickness of the second edge is less than a thickness of the second wall disposed between the second protrusion and the coupling portion.
8. The heat exchanger according to claim 7, wherein a minimum distance between the first edge and the second edge is larger than the maximum width of each heat transfer tube in a section view perpendicular to the heat transfer tubes.
9. The heat exchanger according to claim 1, wherein each second opening is larger than the corresponding first opening when viewed in the first direction, and an edge of each second opening is located outward of an edge of the corresponding first opening when viewed in the first direction.
10. The heat exchanger according to claim 1, further comprising:
- an external plate connected to the first pipe, wherein the first member includes:
- wall surface portions that respectively extend from two ends of the first portion toward the first pipe along the first wall and the second wall, respectively; and
  - claws respectively disposed on ends of the wall surface portions opposite to the first portion,
- the claws extend toward each other, and

22

- the claws are in contact with a surface of the external plate that opposes the first portion.
11. The heat exchanger according to claim 1, wherein each heat transfer tube is a flat tube with a flat face.
12. The heat exchanger according to claim 1, wherein the first pipe is a gas pipe.
13. A heat pump apparatus comprising:
- the heat exchanger according to claim 1.
14. The heat exchanger according to claim 1, wherein the first member has a first wall portion and a second wall portion,
- the first wall portion extends in the first direction from one end of the first portion along the outside of the first wall, and
- the second wall portion extends in the first direction from the other end of the first portion along the outside of the second wall.
15. A heat exchanger connected to a first pipe through which a refrigerant flows, the heat exchanger comprising:
- heat transfer tubes extending in a first direction; and
- a header connected to the heat transfer tubes, wherein the header includes:
- a first member including a first portion connected to the heat transfer tubes; and
  - a second member disposed between the first pipe and the first portion,
- the second member includes:
- a first wall and a second wall that each extend in the first direction;
  - a coupling portion that couples the first wall to the second wall;
  - a first protrusion protruding from the first wall toward the second wall; and
  - a second protrusion protruding from the second wall toward the first wall,
- the first pipe communicates with each heat transfer tube through a space delimited by the first wall and the second wall,
- a longitudinal direction of the first wall and a longitudinal direction of the second wall in a section view along the longitudinal direction of the header are in the first direction,
- the first wall, the second wall, and the coupling portion are plates,
- the first and second protrusions are disposed closer to the heat transfer tubes than the coupling portion,
- a minimum distance between the first protrusion and the second protrusion is shorter than a maximum width of each heat transfer tube in a section view perpendicular to the heat transfer tubes,
- the first wall includes a first edge disposed on a side of the first protrusion disposed closer to the heat transfer tubes than the coupling portion,
- the second wall includes a second edge disposed on a side of the second protrusion disposed closer to the heat transfer tubes than the coupling portion,
- a thickness of the first edge is less than a thickness of the first wall disposed between the first protrusion and the coupling portion, and
- a thickness of the second edge is less than a thickness of the second wall disposed between the second protrusion and the coupling portion.
